UNITED STATES PATENT OFFICE.

JOHN J. SCHWARZ, OF MAYWOOD, NEW JERSEY, ASSIGNOR TO HENRY METZ, OF MAYWOOD, NEW JERSEY.

ENGINE-OVERHAULING INSTALLATION.

Application filed March 25, 1920. Serial No. 368,712.

To all whom it may concern:

Be it known that I, JOHN J. SCHWARZ, a citizen of the United States, residing at Maywood, in the county of Bergen and State 5 of New Jersey, have invented certain new and useful Improvements in Engine-Overhauling Installations, of which the following is a specification.

This invention relates to machines for 10 overhauling engines, and with regard to certain more specific features, the invention has especial utility in connection with T type "Ford" engines.

One of the objects of the invention is to 15 provide an installation by the use of which all of the various operations in the overhauling of an engine can be accomplished with ease and dispatch.

Another object is to provide an installation 20 of the above type by the use of which disassembly, repair, reassembly and testing of the engine can be performed with a minimum of trouble in setting up the engine for said operations.

25 Another object is to provide apparatus of the general type set forth, simple and compact in construction which will permit with a minimum of effort all or any combination of the following steps: disassembly of the 30 engine, reaming of the crank shaft bearings, burning in of the crank shaft and other parts, reassembling of the engine, running in and testing of the engine.

Another object is to provide in apparatus 35 of the type set forth, simple, easily set, and yet effective means for securing the engine in place upon the machine.

Other objects will be in part obvious, in part pointed out hereinafter.

40 The invention accordingly consists in the features of construction, combinations of elements and arrangement of parts which will be pointed out hereinafter, and the scope of the application of which will be pointed 45 out in the following claims.

Referring now to the accompanying drawings in which is shown one of various possible embodiments of the several features of this invention, Fig. 1 is a sectional side view 50 of my machine, a "Ford" engine being shown in dotted lines in place thereon.

Fig. 2 is an end view of my installation.

Fig. 3 is a side elevation partly in section

of the engine carriage showing a "Ford" engine casting in place thereon substantially 55 as in Fig. 1.

Fig. 4 is a detail view of the burning in connection, the driving link being shown broken.

Fig. 5 is a view similar to Fig. 4 of the 60 running in connection, and

Fig. 6 is a view similar to Fig. 4 of the reaming connection.

Similar reference characters refer to similar parts throughout the different views 65 of the drawings.

Referring now to the drawings, I have shown a machine for overhauling engines comprising a bed 1, mounted upon legs 2. Upon the bed there is provided a power 70 shaft 3 mounted in bearings 4, 5, which are located respectively within standards 6 and 7, rising from the bed 1. The delivery end of the power shaft is non-circular as at 69 for effecting a convenient driving connection as will appear below. The standards 6 and 7 also preferably carry near their lower ends the bearings 8 for the clutch shaft 10 to which power for operating upon the engine to be overhauled is transmitted, preferably from an electric motor 11, through a belt 12 or the equivalent, which drives by way of example the drum 13 of a clutch 14.

The power is delivered from clutch shaft 10 to power shaft 3, through a pair of meshing gears 15, 16, the former keyed to the shaft 10, and the latter to the shaft 3; gear 15 being by preference of smaller diameter than gear 16, to effect torque multiplication.

90 The clutch taken per se is of well known construction and not my invention. It may briefly be noted that the same by preference comprises a friction band 9 within the inner periphery of the drum 13 and a lever 17 fulcrumed at one end 18 within the drum and delivering pressure intermediate its ends through a link 19 to friction band 9 for tightening the same. A cone 20 is shiftable upon the clutch shaft 10 by means of a lever 100 22 having a part fitting in a groove 21 in cone 20, the free end of lever 17 having a portion resting upon said cone. It will be understood that the tightening of the clutch is effected by throwing lever 22 whereby the 105 cone is shifted to its extreme left, the cone

thereby moving lever 17 about its fulcrum 18 and tightening the clutch by transmitting pressure to the band 9 through link 19.

Upon the bed there is mounted an engine 5 supporting carriage or frame designated in its entirety by the letter "C". This carriage by preference has a longitudinal axis designated by the line A—A which is in alignment with power shaft 3, said carriage being mounted upon the bed 1 for adjustment 10 about its said axis. For this purpose I preferably provide upon the bed 1 a circular seat 25 preferably secured to the standard 7 by bolts, one of which appears 15 at 60, as best shown in Fig. 1. An arcuate seat 24 is provided near the end of the machine opposite the power shaft, said seat being coaxial with the seat 25. The carriage C by preference comprises a pair of 20 coaxial annular end members or rings 28 and 29 of different diameters, formed rigid with a pair of connecting cross beams 30 and 31, the latter having the greater part of its length parallel to the axis A—A. The 25 cross beams are preferably channel shaped; the channels of the beams 30 and 31 embracing lugs 61, cast integrally with the annular end members 28 and 29. Any suitable means is employed for securing the cross 30 beams to the annular members, such as bolts 70.

The ring 29 is preferably of considerably larger diameter than the ring 28, and rests upon the seat 24. In putting together my 35 assembling machine, the engine carriage C is applied by slipping end member 28 over seat 25, the other end member seating upon seat 27. Any suitable stop, as shown for instance at 62, serves to prevent longitudinal 40 displacement of the carriage. It will be apparent that the carriage may readily be adjusted about its longitudinal axis A—A by raising or depressing one of the cross beams, thus rotating the carriage about its seat 25, 45 and within its seat 24. The manner of supporting the carriage above described is the preferred embodiment, and it will be understood that different forms of mounting may be employed.

50 Means is provided for securing the engine to be overhauled upon the carriage C, this means being preferably such as to permit ready access to all parts of the engine for inspection, disassembly, repair, reassembly, 55 adjustment and the like. By preference this means comprises an engine rest 26 rigidly secured, or if desired, formed as an integral part with the cross beam 31 of the carriage C. The rest is provided with a plurality of troughs 27 within which are disposed the sides of the cylinders of the engine to be repaired.

55 Any appropriate means is provided for rigidly securing the engine to said engine rest, this means by preference extending

in a plane transverse of the engine and intermediate the top and bottom of the cylinder casting, whereby said casting after it is secured to the carriage will remain readily accessible both from the upper and 70 from the lower end thereof.

As above noted, the preferred form of the invention has more particular utility in connection with "Ford" engines. As indicated in dotted lines on Figs. 1 and 3, the "Ford" 75 engine has four cylinders, cast in two pairs 32 and 33 as an integral part with the upper half 63 of the crankcase, there being a space 34 between the cylinder pairs. When my apparatus is used for operating upon an 80 engine of this general type, I employ a bolt 35, having a head 36, said bolt being inserted to extend upwardly as shown in Fig. 3, through the cross beam 31, centrally 85 through said rest 26 and perpendicularly thereabove through the space 34 in the engine block. A nut 37 is then threaded upon the free end of the bolt against the flat surface 38 formed particularly on Ford engines, thereby clamping the engine rigidly and accurately in position.

It will be noted that the sides of the troughs 27 in the rest 26 will limit the engine block against rotation about the bolt 35 and the nut 37 will prevent the engine 95 from undesired displacement along the bolt or removal therefrom, so that the single bolt and nut serve to firmly and accurately retain the entire engine in position upon the carriage, without in the least interfering with ready access to all parts of the engine to be worked upon. It will be understood that other means may be provided for mounting the engine in position, but I prefer to employ the specific means 100 shown and described.

As indicated in Figs. 1 and 3, the parts are preferably so proportioned that when the engine is mounted in position thereon, the axis of the crank shaft will extend along 110 or coincide with the axis A—A of the carriage for a purpose which will appear fully below.

In the use of my apparatus the engine to be overhauled will be bodily laid upon the 115 engine rest 26, with the sides of the cylinders fitting into the troughs 27, and the bolt 35 and nut 37 will be applied to firmly secure the engine in place upon the carriage in the manner already described. Thereupon 120 the engine may easily be disassembled or taken down, the carriage C being turned into convenient position to place the engine in vertical, horizontal, inverted, or other position for most convenient access to the 125 parts as they are to be removed.

The carriage C may be firmly secured in any desired position about its axis by means of a friction strap 39. The strap preferably encircles the end ring 29 and is secured 130

as at 23 to opposite sides of the bed 1. A dead center lock is preferably provided on the strap for securing firm frictional clamping engagement with the carriage. This lock by preference comprises a lever 40 having a fulcrum 42 lodged within an eye 42' in one end of the strap, the opposite end of the strap 39 encircling a stud 41 intermediate the ends of the lever 40, the free end of said lever serving as an operating handle. To tighten the strap the lever 40 is merely depressed and the strap end 44 will thereby be drawn in circumferential direction to perform the securing function. By raising 10 the end of the lever 40 the strap is rendered ineffective, opened or unlocked.

After the engine has been disassembled as above described, the carriage is clamped in such position as to dispose the engine 20 block in inverted position. The main crank shaft bearings are now replaced and are reamed by power applied from the power shaft 3.

By preference the assembly shown in detail in Fig. 6 is used for operating the reaming tool 48 from the power shaft 3. This assembly comprises an adapter 46, having a non-circular opening snugly embracing the end 69 of the power shaft 3, the adapter including a cylindrical shell bifurcated by longitudinal slots as at 47. A connecting link 45 fits loosely into the adapter shell, and has a pair of pins 49 projecting into said slots, thus constituting a universal connection. The reaming tool 48 which is of known construction is attached by a second universal driving connection 52 to the free end of the link 45. The link is threaded as at 50 for a substantial part of its length, 40 and a nut 51 cooperates with said threaded portion,

The detailed process of carrying out the reaming operation consists in first applying the assembly of Fig. 6 in place between the power shaft and the engine casting in a manner which is obvious. Power is then applied by starting the electrical motor 11 and tightening the clutch 14 by shifting the clutch lever 22, whereby the power shaft 3 is driven. The nut 51 is then grasped by a pair of tongs or the like and held against rotation, whereby the link 45 will feed forwardly by reason of the threaded connection and the reamer will simultaneously 50 work its way through the three bearings for the well known purpose.

As shown in the drawings the engine is mounted at a substantial distance from the power shaft 3, so that the connecting link 45 for transmitting power to the reamer must be of substantial length. Should the crank shaft axis be inaccurately aligned with the continuation of the power shaft, the relatively long link by reason of the universal connections will nevertheless cause

the reamer to feed properly along the crankshaft axis.

The reaming operation having been completed, the reaming connection is removed, the crankshaft is inserted in place within 70 its bearings, and said bearings are then tightened to firmly grip the crankshaft. The crankshaft is now ready for the "burning in" process, that is, the process of rotating the crankshaft under power for heating 75 the bearings and rendering them plastic to cause them to assume the proper dimensions required in use, this process being old and well known.

For transmitting the power for "burning in" the assembly shown in Fig. 4 is employed. An adapter 64 is employed similar to adapter 46 heretofore described but materially shorter. A driving link 53 has a pair of transverse pins 54 fitting in the slots 85 47 of the adapter 64.

The opposite end of link 53 has a pair of pins 57 preferably at right angles to pins 54, and fitting into a pair of slots 56 in a sleeve 55. This sleeve is mounted upon the 90 end of the engine crankshaft, and has recesses 65 straddling the pins 58 formed as part of the standard construction of Ford engine crankshafts. As pins 58 may be too weak to transmit the considerable power required in the "burning in" process, I surround the sleeve 55 by means of a clamping ring 59, which relieves the torque from the pins 58, thus preventing shearing thereof.

The "burning in" of the crankshaft being completed, the pistons may now be inserted into the cylinders, and the connecting rod bearings tightened upon the throws of the crankshaft. For this assembling operation, 105 it is of course obvious that the carriage C may readily be turned to the position most convenient to the mechanic, the clamp 39 having first been opened, and after such position is reached said clamp may again be 110 tightened to secure the carriage C in the adjusted position. Power is now again applied through the connecting link shown in Fig. 4 for the purpose of "burning in" the connecting rod bearings, and running in the 115 pistons, and the piston rings.

The running in operation completed, the connecting link shown in Fig. 4 is removed, the clamp 39 is opened and the carriage C is rotated to and clamped in convenient position for the reaming of the valve guides, whereupon the valves may be ground. The engine may now be replaced, as well as the flywheel assembly which includes the magneto in Ford engines. The latter elements 125 can conveniently be passed through the annular end member 29 of larger diameter. At this stage the connection of Fig. 4 may conveniently be employed to transmit driving power to the engine crankshaft from the 130

4
electric motor 11 for the purpose of testing the magneto. The transmission may now be passed through ring 29 and secured in place and the lower half of the crankcase may be bolted in place, thus completing the assembly.

The carriage C is now rotated to place the engine in upright position and power may be applied from motor 11 for limbering up the engine. By preference this power is applied through the assembly shown in Fig. 5. This assembly includes the same adapter 64 shown in the assembly of Fig. 4, and a driving link 66 similar to link 53 which should be of smaller diameter to fit into the crankcase. A sleeve 67 generally similar to sleeve 55 connects the engine crankshaft to be driven from the adjacent end of link 66.

After the motor is limbered up, the spark plugs are put into the cylinder head and the various fuel, ignition and cooling water connections are made, whereupon the engine may be tested by running it under its own power while still mounted upon the carriage C in its original position.

It will be apparent that in running the motor in under its own power the connecting link arrangement shown in Fig. 5 may be employed to crank the engine prior to starting by power from motor 11 transmitted through the power shaft 3. Ratchet teeth 68 are formed upon sleeve 67 for cooperation with pins 58 on the engine crankshaft, said ratchet teeth allowing the engine to run freely when it starts firing.

It will be understood that the universal connection of the links shown in Figs. 4 and 5 will compensate for any small lateral displacement of the crankshaft axis with respect to the power shaft, as in the case of the reaming connection above described.

The engine should now be in satisfactory running condition and can be reapplied to the vehicle. For this purpose it is merely necessary to remove the single bolt 35 when the completely assembled and tested engine is free to be taken off the assembling machine.

The various steps that can be performed upon my assembling machine will now be briefly reviewed.

The engine is first set in place upon the carriage C. It is then disassembled until nothing but the cylinder casting is left in place upon the carriage. The main bearings are now replaced and reamed by power through the machine. Next, the crankshaft is replaced and burned in, the power being applied direct to said crankshaft. Then the pistons are inserted into the cylinders and the connecting rod bearings are clamped about the crankshaft, whereupon power is again applied to the engine for running in the latter parts. Thereupon, the valve guides are reamed and the valves ground, the

head replaced and the flywheel assembly including the magneto, reapplied. Power may now be applied to the crankshaft for testing the magneto. The engine may now be completely assembled and can then be limbered up by power applied to the crankshaft. After this limbering up process the spark plugs are put into the cylinder head, the fuel, ignition, and cooling water connections are made and the motor is run in under its own power for test purposes, being first conveniently cranked by power delivered from the power shaft.

The above steps, which constitute all of the steps ordinarily required in overhauling an engine, require but a single mounting operation of the engine casting upon the carriage. When once the engine is mounted in place by the single bolt 35, the engine can be turned to the position most convenient for performing each and every one of the above steps thereon, all by the simple process of opening the clamp 44, turning the carriage C until the proper position is reached and again locking the clamp.

It is of course apparent that all of the above steps need not be performed in every case and that the order of steps above pointed out need not always be strictly followed.

It should particularly be noted that as the crankshaft axis of the engine when mounted in position coincides with axis A—A of the carriage C, and as the latter axis is aligned with or on the continuation of power shaft 3, power is readily transmitted from said shaft 3 to the crankshaft or reaming tool, regardless to what position the carriage is rotated.

Although the parts are so designed that the crankshaft of the engine when mounted in position upon the carriage C is coaxial therewith, it will be understood that certain of the advantages of my construction can be secured if the engine be secured with its crankshaft axis parallel to the carriage axis instead of coincident therewith, in which event, the crankshaft would be aligned with the power shaft when the carriage is set in some one predetermined position.

Finally, it should be noted that although the specific installation shown and described has especial application to "Ford" engines, the broader features of the invention are applicable to the overhauling of various types of engines.

It will thus be seen that there is herein described apparatus in which the several features of this invention are embodied, and which apparatus in its action attains the various objects of the invention and is well suited to meet the requirements of practical use.

As many changes could be made in the above construction and many apparently

widely different embodiments of this invention could be made without departing from the scope thereof, it is intended that all matter contained in the above description or 5 shown in the accompanying drawings shall be interpreted as illustrative and not in a limiting sense.

I claim:

1. In an engine overhauling machine, in combination, a bed, an engine supporting member thereon provided with means for rigidly mounting an engine casting, said supporting member being adjustable to allow ready access to different parts of the 10 engine for repair and assembly, and means on said bed adapted to transmit mechanical power to said engine for repair purposes in inverted position.
2. In an engine overhauling machine, in combination, a bed, an engine supporting member thereon provided with means for rigidly mounting an engine casting, means for securing said supporting member in any 15 of a variety of positions about the longitudinal axis thereof to allow ready access to different parts of the engine for repair and assembly, and means on said bed aligned with the engine shaft both when the supporting member is secured for erect and 20 when it is secured for inverted position of the engine to transmit mechanical power thereto in either said position.
3. In an engine overhauling machine, in combination, a bed, an engine supporting member thereon provided with means for rigidly mounting an engine casting, an arcuate seat on said bed for said supporting member, means securing said supporting member in said seat in any of a plurality of 25 positions to allow ready access to different parts of the engine for inspection and repair, and a power shaft on said bed for transmitting power to said engine for burning in of the bearings, said parts being so disposed relative to each other that when an 30 engine is properly mounted on said supporting member and the latter is secured in inverted position in its arcuate seat the crank-shaft of the engine is aligned with 35 said power shaft.
4. In an engine overhauling machine, in combination, a bed, an engine supporting member, means for mounting an engine casting on said supporting member, stand- 40 ards on said bed for carrying said supporting member, and permitting rotary adjustment of the latter about the longitudinal axis thereof to allow ready access to different parts of the engine for repair and assembly, means for securing said supporting member in any position to which it may be 45 adjusted, a power shaft on said bed aligned with the crankshaft of an engine when in place on said supporting member, and means 50 passing through a recess in the end of said

supporting member for establishing a power connection between said power shaft and said engine.

5. In an engine overhauling machine, in combination, a bed, means for mounting an engine casting thereon, with the axis of the crankshaft thereof in a single fixed position, means for securing said casting in any of a plurality of positions about said fixed axis of the crankshaft, and a power shaft on said bed aligned with said axis.

6. In an engine overhauling machine, in combination, a bed, an engine supporting member having a circular portion resting on said bed, means for securing an engine casting to said support with the crankshaft axis of said casting coaxial with said circular portion and means for securing said casting with respect to said bed in any of a plurality of positions which it may assume by rotating the circular support portion about its center upon said bed, whereby said crankshaft axis will remain in a fixed position in any said position of said casting.

7. In an engine overhauling machine, in combination, a bed, a pair of arcuate seats thereon, an engine supporting member having a pair of circular portions revolvably resting upon said arcuate seats, said support having means for securing an engine casting thereto with the crankshaft axis of the latter coaxial of said circular portions, means clamping said supporting member to said bed in any position to which it may be adjusted on said seats, one said circular portion having a central opening to permit power connection with the crankshaft.

8. In an engine overhauling machine, in combination, a bed, an engine supporting member having a pair of circular portions and a beam connecting the same, arcuate seats on said bed for said circular portions, means for securing an engine casting to said beam with the crankshaft axis thereof coaxial with said circular portions, means clamping one of said circular portions in any position to which said supporting member may be rotated upon said seats, and a power shaft on said bed, aligned with said crankshaft axis, whereby a power connection may be established with said engine through an aligned opening in the circular portion adjoining said power shaft.

9. In an engine overhauling machine, in combination, a bed, a power shaft and an engine supporting member mounted upon said bed, said supporting member being adapted to carry an engine casting rigidly secured thereto, said supporting member being readily adjustable to dispose said casting in inverted or in erect position, the parts being constructed and arranged such that the crankshaft axis is aligned with said power shaft when the block is in inverted

position for ready reaming and burning in of the crankshaft bearings, and means for securing said supporting member to said bed with said engine in said erect position 5 to allow running of the latter under its own power in its original position with respect to said support.

10. In an engine overhauling machine, in combination, a bed, a power shaft and an engine supporting member upon said bed, said supporting member resting revolvably upon said bed to permit adjustment of the same about a longitudinal axis thereof whereby an engine casting carried by said 15 supporting member may be placed in convenient position for each step in the repair and assembly of the engine; the elements of said overhauling machine being constructed and arranged such that the crankshaft axis of said casting is aligned with said power shaft when the casting is in inverted position to permit ready reaming and burning in of the crankshaft bearings, and means for securing said supporting 20 member to said bed with said engine in erect position to allow running in of the latter under its own power in its original position with respect to said support.

11. In an engine overhauling machine, in combination, a bed, a power shaft thereon, longitudinally spaced and aligned arcuate seats upon said bed, an engine supporting member having an intermediate member and circular end members, the latter resting 35 revolvably in said seats, and being coaxial with said power shaft, means for rigidly securing an engine casting to said intermediate member, with the crankshaft axis of said casting aligned with said power shaft, and a 40 severable power connection between said power shaft and said engine, whereby the crankshaft bearings may be readily reamed from said power shaft, the bearing members may be applied, and burned in by power from said shaft, the parts of the engine may 45 be readily assembled upon said casting, and said supporting member may be turned to place said engine in vertical position to permit testing of the same under its own power 50 in its original mounting with respect to said supporting member.

12. The combination in an engine overhauling machine, of a bed, a power shaft thereon, an engine supporting member mounted upon said bed for rotary adjustment about its longitudinal axis, means for securing said supporting member in any 55 position of adjustment, means for rigidly mounting an engine upon said supporting 60 member with the crankshaft axis thereof aligned with said power shaft, to permit burning in of the crankshaft by power from said power shaft, whereby after the burning in process, said supporting member may be 65 rotated and secured in position to dispose

said engine in upright position, to permit the latter to be tested under its own power in its original mounting with respect to said supporting member.

13. The combination in an engine repairing machine, of a bed, a power shaft thereon, an engine supporting member comprising an intermediate element, and circular end portions, the latter coaxial with said power shaft, arcuate seats on said bed 70 for said end portions whereby said supporting member is revolvably mounted in said seats, means for clamping said supporting member in any position of adjustment, and means on said supporting member for rigidly securing a "Ford" engine thereon with the crankshaft axis of said engine aligned with said power shaft, to permit burning in of the crankshaft by 75 power from said power shaft. 80

14. The combination in an engine overhauling machine, of a bed, a power shaft thereon, an engine carriage on said bed, adapted to have mounted thereon an engine casting with the crankshaft axis thereof substantially aligned with said power shaft, a 90 tool for reaming the crankshaft bearings and a link connecting said power shaft with said tool, said link having a universal connection at each end. 95

15. A carriage for an overhauling machine for engines comprising a pair of coaxial ring members, one of larger diameter than the other, a cross beam rigidly connecting said rings, said cross beam having 100 an engine supporting part, said part being parallel to the axis of said carriage.

16. A carriage for an overhauling machine for engines comprising a pair of coaxial ring members one of larger diameter 105 than the other, a pair of channel cross beams rigidly connecting said rings, one said cross beam having a substantial part of its length parallel to the axis of said carriage, and an engine rest upon said part. 110

17. The combination in an engine overhauling machine, of a bed, a power shaft thereon, an engine carriage on said bed having the axis thereof aligned with said power shaft, and adapted to have mounted thereon 115 an engine to be overhauled, in such manner as to dispose the crankshaft axis thereof in substantial alignment with said power shaft, and at a substantial distance therefrom, and a removable link for connecting said power 120 shaft and said crankshaft of said engine, said link having a universal driving connection at each end.

18. The combination in an engine overhauling machine for "Ford" engines, of a 125 bed, a power shaft thereon, an engine carriage adjustable about a fixed axis on said bed, means for coaction with an engine casting intermediate the ends thereof for securing the same to said carriage with the crank- 130

- shaft axis thereof substantially aligned with said power shaft, in every position of adjustment of said carriage, whereby when the engine is mounted on the carriage with the 5 front end thereof nearest said power shaft, a power connection may be established between said power shaft and said crankshaft for burning in the latter, and whereby the flywheel assembly including the magneto 10 may readily be assembled upon the engine casting without disturbing said securing means, and whereby the crankshaft may then be driven from said power shaft for testing said magneto.
- 15 19. The combination in an overhauling engine, of a bed, a power shaft thereon, an engine carriage on said bed, said carriage having a large open end portion remote from said power shaft to facilitate assembly of
- 20 engine parts therethrough and an open portion on the end nearest said power shaft, to permit application of power from said power shaft to the engine to be overhauled, and means for securing said engine to said car-

riage, said means being disposed intermediate 25 the top and bottom as well as intermediate the ends of the cylinder casting of said engine, to permit all overhauling steps to be readily performed.

20. The combination in an overhauling 30 engine, of a bed, a power shaft thereon, an engine carriage on said bed, said carriage having a large open end portion remote from said power shaft to facilitate assembly 35 of engine parts therethrough and an open portion on the end nearest said power shaft, to permit application of power from said power shaft to the engine to be overhauled, and means permitting adjustment of said carriage about an axis, for placing 40 the engine thereon in most convenient position for each operation to be performed thereon.

In testimony whereof, I have signed my name to this specification this 23rd day of 45 March 1920.

JOHN J. SCHWARZ.
